US00D745927S

(12) **United States Design Patent**
Hardy et al.(10) **Patent No.:** **US D745,927 S**
(45) **Date of Patent:** **** Dec. 22, 2015**(54) **HUMAN MODEL**

- (71) Applicant: **Design Ideas, Ltd.**, Springfield, IL (US)
- (72) Inventors: **Christopher T. Hardy**, Springfield, IL (US); **Keying Zhang**, Zhejiang (CN)
- (73) Assignee: **Design Ideas, Ltd.**, Springfield, IL (US)
- (**) Term: **14 Years**
- (21) Appl. No.: **29/464,688**
- (22) Filed: **Aug. 20, 2013**

Related U.S. Application Data

- (63) Continuation of application No. 29/447,022, filed on Feb. 28, 2013, now Pat. No. Des. 691,210, which is a continuation of application No. 29/410,960, filed on Jan. 13, 2012, now Pat. No. Des. 680,589, which is a continuation of application No. 13/286,866, filed on Nov. 1, 2011, now abandoned.

Primary Examiner — Mary Ann Calabrese*(74) Attorney, Agent, or Firm* — Saidman DesignLaw Group, LLC**(57) CLAIM**

The ornamental design for a human model, as shown and described.

DESCRIPTION

FIG. 1 is a front view of a human model showing our new design;

FIG. 2 is a side perspective view thereof;

FIG. 3 is a front perspective view thereof; and,

FIG. 4 is an alternative front perspective view thereof. The broken lines illustrate environmental structure and form no part of the claimed design.
